UNITED STATES PATENT OFFICE.

GEORGE D. SICKLESTEEL, OF ROSEBURG, OREGON.

BOAT-MOTOR.

1,134,919.

Specification of Letters Patent. Patented Apr. 6, 1915.

Application filed August 29, 1914. Serial No. 859,175.

To all whom it may concern:

Be it known that I, GEORGE D. SICKLESTEEL, a citizen of the United States, residing at Roseburg, in the county of Douglas 5 and State of Oregon, have invented new and useful Improvements in Boat-Motors, of which the following is a specification.

This invention relates to boat motors, the object in view being to produce a simple and effective motor especially adapted for use in boats, said motor being manually operated either by the hands or feet, or both the hands and feet, of the operator who sits facing the bow of the boat.

15 A further object of the invention is to provide in connection with the hand operable motor actuating levers, steering levers so connected with the rudder that they may be operated simultaneously with the hand 20 propelling levers for directing the course of the boat.

With the above and other objects in view, the invention consists in the novel construction, combination and arrangement of parts, 25 as herein described, illustrated and claimed.

In the accompanying drawings:—Figure 1 is a vertical longitudinal section through a boat equipped with the manually operated motor of this invention, the motor being 30 shown for a greater part in side elevation; Fig. 2 is a plan view of the same; Fig. 3 is an enlarged plan view of the motor, with parts broken away in section; and Fig. 4 is an enlarged fragmentary detail of one of the 35 propelling levers, showing also the hand steering levers.

Referring to the drawings, 1 designates a boat of any suitable construction and dimensions, the same being shown as resembling in shape and size an ordinary row boat 40 provided with a rudder 2 carried by a rudder post 3 having fixed on the upper end thereof a cross head 4, to which the steering connections hereinafter described are attached.

In carrying out the invention I provide a motor supporting frame which is conveniently shown as comprising the transverse sills 5 connected by the longitudinal stringers 6, said frame as a whole being securely fastened in the bottom of the boat as shown in Fig. 1.

7 designates the propeller shaft which is journaled in bearings 8 and 9, the latter being supported by an additional tie bar 10 terminally fastened at its opposite ends to

the longitudinal stringers 6. The propeller shaft 7 is shown as provided with a fly-wheel 11 between the bearings 8 and 9 and the rear end portion of said propeller shaft passes through a stuffing box 12 in the keel of the boat beyond which it has fast thereon a propeller 13 of any suitable type.

At its forward extremity the propeller shaft 7 has fast thereon a beveled pinion 14 which meshes with and is driven by a large beveled gear wheel 15 fixed on a rear crank shaft 16, the latter being journaled in bearings 17 on one of the cross sills 5 of the motor frame and other bearings 18 on the longitudinal stringers 6. In advance of the crank shaft 6 and extending parallel therewith is a forward crank shaft embodying the two sections *a* and *b* divided centrally from each other as shown in Fig. 3 and 75 journaled in bearings 19 which may be fastened to the bottom of the boat or any other convenient support. On the outer ends of the sectional shaft *a*, *b* are fastened crank arms 20 from which link rods 21 extend 80 rearwardly, where they are journaled on other crank arms 22 fast on the opposite extremities of the crank shaft 16. The crank shaft sections *a* and *b* are provided with the oscillatory foot cranks 23 by means of which 85 the operator by extending and retracting his legs may oscillate the forward crank shaft and thereby through the medium of the link rods 21 impart a rotary movement to the rear crank shaft 16. Hand propelling levers 90 24 are journaled intermediate their ends on an elevated shaft 25. To the lower end of each of the hand levers 24 there is attached a connecting rod or pitman 25', the opposite end of which is connected to one of a pair of cranks 26, with which the shaft 16 is provided. Thus the levers 24 are used in conjunction with the foot cranks 23 enabling the combined power of the arms and legs to be utilized for driving the propeller 13. 100 It is also preferred to arrange the cranks and connections in such manner that when the right arm, for example, is drawn backwardly the right leg is extended and the same arrangement is provided with regards 105 to the other hand and foot operating elements. This enables the operator to utilize the muscles of his arms and legs to the best advantage, adapting the boat to be propelled at the maximum speed with the minimum 110 amount of effort on part of the operator. It will furthermore be observed that the

operator may use his feet to propel the boat while his hands remain idle or vice versa.

The steering apparatus comprises a pair of hand steering levers 27 of bell crank 5 form as illustrated in Figs. 1 and 4, each of said levers being pivotally mounted at 28 on the respective hand propelling levers 24 and being limited as to its movement in one direction by means of stops 29 and 30 located 10 respectively on the levers 27 and 24 as shown in Fig. 4. To the levers 27 are attached the forward extremities of rearwardly extending wires or cables 31, each of which has incorporated therein a contractile 15 tile spring 32. The wires or cables 31 are connected at their rear extremities to the opposite extremities of the cross head 4, the springs 32 serving to take up slack in the steering connections 31, avoiding lost motion 20 and normally sustaining the rudder 2 in a central position so as to steer the boat in a straight away direction. Either of the steering hand levers 27 may be operated independently of the other, the appropriate 25 spring 32 allowing for the necessary stretch of one of the steering connections 31 to permit the rudder to be turned to one side or the other.

The bearings 19 of the forward crank 30 shaft are supported at an elevation as shown in Fig. 1 as by means of one or more posts 33. 34 designates braces connecting said posts with the bottom of the boat. 35 designates the operator's seat and 36 the 35 passenger's seat located in advance of the operator's seat. Additional seats 37, 38 and 39 may be provided as found desirable. The bearing 9 is preferably of the anti-friction ball type as illustrated in Fig. 3, so as to 40 reduce friction adjacent to the intermeshing point of the wheels 14 and 15.

From the foregoing description, taken in connection with the accompanying drawings, it will now be understood that the motor 45 is adapted to be driven by a single operator who may use either his hands or feet or both and that the steering of the boat is effected by the levers 27 mounted upon and carried by the hand propelling levers 24, 50 the operation of the levers 24 not interfering

with the steering connections by means of the fact that the flexible cables or wires 31 pass around guiding sheaves or pulleys 40 on the shafts or rods 25 which are coincident with the axes of movement of the hand levers 24. Therefore, the operation of the levers 24 will not affect the steering connections. It will also be noted that the major portion of the motor is located under the operator's seat where it is out of the way and takes up very little valuable space.

I claim:—

1. A boat motor comprising a motor supporting frame, a pair of crank shafts arranged one in advance of the other and in different horizontal planes, the forward crank shaft being provided with a pair of oscillatory foot cranks and being connected to the rear crank shaft for simultaneous operation, hand controlling levers operatively associated with the rear crank shaft, a propeller shaft geared to one of said crank shafts, hand steering levers mounted on and carried by the hand controlling levers, and steering connections leading from said hand steering levers to the rudder.

2. A boat motor comprising a motor supporting frame, a pair of crank shafts arranged one in advance of the other and in different horizontal planes, the forward crank shaft being provided with a pair of oscillatory foot cranks and being connected to the rear crank shaft for simultaneous operation, hand controlling levers operatively associated with the rear crank shaft, a propeller shaft geared to one of said crank shafts, hand steering levers mounted on and carried by the hand controlling levers, steering connections leading from said hand steering levers to the rudder, and guiding sheaves around which the steering connections pass, said sheaves having their axes co-incident with the axes of movement of the hand propelling levers.

In testimony whereof I affix my signature in presence of two witnesses.

GEORGE D. SICKLESTEEL.
